[57] CLAIM

The ornamental design for a receiver for a golf ball chipping game, as shown and described.

DESCRIPTION

FIG. 1 is a perspective view of our new design for a receiver for a golf ball chipping game;

FIG. 2 is a plan view of the same;

FIG. 3 is a front elevational view of the plan shown at FIG. 2;

FIG. 4 is a transverse sectional view as taken from the indicated line 4—4 at FIG. 2; and

FIG. 5 is a sectional view as taken from the indicated line 5—5 at FIG. 2.

The underside view appears the same as the plan view at FIG. 2 with the components being reversed.
